US0D1101046S

(12) **United States Design Patent** (10) Patent No.: **US D1,101,046 S**
(45) Date of Patent: ** Nov. 4, 2025

(54) **DISPLAY**

(71) Applicant: **Motorola Mobility LLC**, Wilmington, DE (US)

(72) Inventors: **James Sloss**, Chicago, IL (US); **Steve C Emmert**, McHenry, IL (US)

(73) Assignee: **Motorola Mobility LLC**, Chicago, IL (US)

(**) Term: **15 Years**

(21) Appl. No.: **29/914,864**

(22) Filed: **Oct. 23, 2023**

(51) LOC (15) Cl. **14-03**

(52) U.S. Cl. USPC ..... **D14/138 AB**

(58) **Field of Classification Search**

USPC ..... D14/336, 374, 432, 440, 126, 341, 344, D14/138 R-138 G, 203.5

CPC G06F 1/1626; G06F 1/1652

See application file for complete search history.
